UNITED STATES PATENT OFFICE.

DUDLEY GARST, OF WATERLOO, IOWA.

STRAW-SPREADER.

1,147,012.

Specification of Letters Patent. Patented July 20, 1915.

Application filed October 19, 1914. Serial No. 867,376.

To all whom it may concern:

Be it known that I, DUDLEY GARST, a citizen of the United States of America, residing at Waterloo, in the county of Blackhawk and State of Iowa, have invented certain new and useful Improvements in Straw-Spreaders, of which the following is a specification, reference being had therein to the accompanying drawings.

In the operation of straw spreaders it is desirable that the load be evenly distributed under all conditions of service and that there be uniform operation of the device whether there be a full or part load therein so that the amount delivered is the same at the beginning of the take off of the load as it is at the last end. It is also desirable to adjust the feeding devices to meet various conditions of the material handled as well as those under which the machine is working.

This invention relates to a straw spreader wherein provision is made for preventing binding of the load as it settles, for imposing even feeding conditions upon the load and for maintaining a constant delivery that is entirely independent of the amount of straw in the machine.

The invention also includes a rack construction whereby capacity and width are secured and the rack made applicable to a running gear of narrow tread; and further to means for regulating feeding and tensioning devices and for other adjustments that are advisable in this type of machine.

In the drawings, Figure 1 is a view in side elevation of a straw spreader that embodies features of the invention; Fig. 2 is a view in elevation of the opposite side of the machine; Fig. 3 is a view in rear elevation of the machine; Fig. 4 is a plan view of a part of the machine with parts removed to prevent confusion; Fig. 5 is a plan view of a portion of the machine body with adjusting driving mechanism and chain wheel guards; Fig. 6 is a view in detail in side elevation showing a main driving gear in idle position; Fig. 7 is a view in detail of a sprocket adjustment; Figs. 8 and 9 are views in detail of a differential driving mechanism; Fig. 10 is a view in detail of an adjustable shaft bearing; Fig. 11 is a view in detail of a spring shifting fork; Fig. 12 is a side elevation of the rack or body showing certain modifications in the construction; and Fig. 13 is a rear end elevation of the same.

Referring to the drawings, a running gear

of the usual type has front bearing wheels 1, rear traction bearing wheels 2 and bolsters 3 of any preferred design, connected by a reach 4 in the usual manner. Longitudinal sills 5 rest on these bolsters and carry transverse members 6 that span and extend laterally beyond the driving or traction wheels to give the desired width to the rack and provide the necessary carrying capacity for the machine. Stanchions 7 are secured by suitable strap braces 10 to the outer end portions of the cross piece 6 in an inwardly inclined position. Longitudinal strips 8 of suitable material connect these stanchions and with suitably disposed forward rack members 9 complete a closed rack that is wider at the base than at the top and that is narrower at the front than at the rear, this latter result being obtained by a suitable proportioning of the cross members 6 and consequent disposition of the stanchions. To facilitate loading, the front and intermediate stanchions are made in sections, the upper section 12 of each being hinged or pivoted to the lower fixed part as indicated at 13, and the adjacent strips 8 being likewise severed to form hinged side portions. When in raised or closed position, these sides are locked in place by latch bars 14 that may be simultaneously operated by a handle bar 15 to engage latch plates 16, the latch bar being extended downwardly so as to be readily accessible to a person standing beside the machine.

A main shaft 17 is journaled in any suitable manner transversely of the main sills 5, preferably to the rear of the traction driving wheels 2 and a pair of main driving sprockets 18 are mounted on the traction wheels 2. In preferred form these sprockets are annular with carrying bolts 19 supporting them on the wheel spokes 20, oppositely disposed check nuts 21 (Fig. 7) permitting lateral adjustment. A pair of sprocket pinions 22 are secured on the shaft 17 in alignment with the main sprockets 18 to engage sprocket chains 23; the upper run of each of which passes over an idler 24 and around a throw out pinion 25 located at the forward side of its sprocket 18. The sprockets 22 are each connected by suitable differential mechanisms to the shaft 17, which comprises, as shown in Figs. 8 and 9, a disk 26 made fast to the shaft 17 and provided with a hub 27 on which a hub 28 of a sprocket 22 is rotatable. A swinging dog 29 carried by the

disk engages projections 29 on the sleeve 27, a spring 30 being provided to hold the dog in engagement therewith and cause the sprocket and shaft to turn together in one direction. A rock shaft 31 is mounted across the sills 5 the forward side of the traction wheels 2, preferably in bearings that are adjustable longitudinally of the sills and constructed as shown, in Fig. 10 with an under block 32, a cap 33 and holding bolts 34 that pass through longitudinal slots 35 in the superposed parts. A rock arm 36 on the rock shaft, is operated by a throw-in lever 37 which is adjacent the driver's station, and is preferably connected to the rock arm by a longitudinally yieldable connection afforded by a rod 38 that passes through a fork 39 pivotally attached to the arm and through a spring 40 that is in compression between the fork base and a suitable plate or keeper 41 on the end of the rod. When in forward position the lever 37 interlocks with a latch plate 42. A pair of depending rock arms 43 on the rock shaft 31 each carry one of the idler sprocket pinions 25, and these arms are in turn articulated by links 44 to swinging levers 45 pivoted at one end to the sills 5 or other convenient support and are in turn connected at their free ends by links 46 to swinging arms also pivoted to the sills at the rear of the traction wheels and carrying at their free ends, idlers 47 to engage the lower runs of the chains 23 when the lever 37 is swung forwardly to swing the sprockets 25 upwardly and raise the chain out of contact with the driving sprockets 18. The idlers 47 are thus swung upwardly simultaneously with the sprockets 25 and form supports for the lower runs of the chains to hold them out of engagement with the driving sprockets on the traction wheels and in engagement with the under side of the idlers 24 which are provided with flanges overlapping the sprockets to guide the chains into and out of engagement with the teeth of the sprockets. The swinging idlers 47 also serve to take up the slack in the chains.

A carrier drive shaft 93 extending across the rear end of the machine has driving sprockets 48 disposed in pairs thereon to engage sprocket chains 50 forming side members of endless conveyors each comprising a pair of said chains and cross bars 53. These carrier chains pass forwardly over a suitable bottom or floor for the rack and around idler sprockets 51 on shafts 52 at the front end of the machine, there being a separate shaft 52 for each carrier to provide for differences in the chains. The cross members 53 of one carrier are preferably arranged in staggered relation to those of the other carriers to more evenly engage the load and lessen the drag on the floor. There is a great advantage in the construction in

which longitudinal sills 5 for supporting the rack are employed, as these sills rest directly upon the bolsters and supporting the cross members which support the floor and extend the full width of the rack with the sides of the rack secured directly thereto. Such sills interfere with the use of a single endless carrier but by providing a plurality of independent carriers to travel in the spaces between the sills and between each sill and the rack side, a light, cheap and rigid construction is secured. To prevent the outer carriers from striking the traction wheels, wheel guards 94 may be provided if necessary.

Variable intermittent motion from front to rear is given to the endless conveyors by means of a ratchet wheel 52 on one end of the main shaft 93, operated by a pawl 53 pivoted on an arm 54 that is pivotally attached at one end to the rack side by a stud 55 or the like. A crank disk 56 on a counter shaft 57 driven by suitable sprocket and chain connections, indicated generally at 58 (Fig. 2) from the main shaft 17, has a crank pin 59 that is coupled to the lever 54 by a link 60. Variable stroke is given to the lever 54 by a shiftable adjustment of the pin 59 which is mounted on an arm 61 pivoted at one end to the disk 56 and adjustably secured at its opposite end to the plate by a clamping screw 62 movable in a curved slot 63 in the disk so that by swinging the arm the crank pin may be moved toward or from the axis of rotation of the disk. The link 60 may also be shifted on the bar 54 with which it has a sliding block connection indicated at 65, said block being shifted longitudinally by means of a hand lever 66 connected to the block by rods 67 and 68. A dog 69 engaging the ratchet wheel 52 prevents retrograde movement of the parts. This arrangement gives any desired throw and provides the preferred intermittent movement.

A beater drum 70 is secured on the shaft 57 and is provided with fingers 71 that are preferably obliquely disposed as indicated. A companion drum 72 with similarly disposed fingers 73 is journaled in spaced relation above the shaft 57 on the rear rack stanchions and is operated from said shaft by sprockets 74 and a chain 75. A pressure shaft 76 on the upper part of the rack at its rear end carries forwardly extending pressure fingers 77 with upturned forward ends, and reinforcements 78 or stiffening bars are preferably added thereto. If left free to swing about the shaft 76 the pressure fingers will follow the load down as it settles down in the rack, but in order to raise them out of the way in loading and to hold them in adjusted position, a hand crank 79 is mounted on the rack side within convenient reach of a person standing on the ground and is se- 130

cured to a pulley 82 connected as by a belt 80 or a like flexible connection, with a pulley 81 on the shaft 76, a dog 83 and ratchet wheel 84 being provided to hold the pulley 82 against turning and the fingers in the desired position.

In order to increase the pressure of the bars 77 upon the load beyond their weight when turned down upon the load with the 10 dog 83 disengaged from the wheel 84, a tensioning device is employed. This device is preferably in the form of a segmental arm 85 pivoted to the side of the rack in the path of the end portions of a forked plate 86 that 15 is secured to the shaft 76. The downwardly projecting end portion 87 of the yoke 85 is yieldingly connected as by a spring 88 with a lever 89 which is operated by a rod 90 having a forward end portion provided with 20 a handle 92 and notches to adjustably interlock with a suitable member 91 near the forward end of the rack. By swinging the yoke 85 in either direction, the necessary frictional engagement to produce the desired 25 result, obtains between the yoke and the fork plate, thereby yieldingly turning the bars with the desired yielding pressure into contact with the load, said bars or fingers, the shaft 76 and pulleys 81 and 82, being free to 30 turn, as the dog 83 is always disengaged from its ratchet except when it is desired to hold the shaft and fingers against turning.

It will be noted in the construction of the 35 rack, the two stanchions 7 at the rear end of each rack side are of full length, extending to the top of the frame and forming a suitable rigid frame work for supporting the beaters and presser bars, the longitudinal strips 8 being severed just forwardly of these 40 stanchions and secured to the upper end portions 12 of the other stanchions to form the hinged sides of the rack. As illustrated in the modified construction shown in Figs. 12 and 13, this supporting frame work is arranged to further increase its strength and 45 rigidity by extending the stanchions 95 and 96 downward to the horizontal plane of the lower edges of the sills 5 and connecting the stanchions 95 by a cross bar 97 which is secured to the rear ends of the sills. The part 50 of each rack side which extends upward at the end of each hinged portion is made strong and rigid by a diagonal brace 98 secured to the stanchions 95 and 96 near their 55 inner ends and extending downwardly and forwardly below the lower edge of the hinged part. That portion of the rack upon which the greatest strain comes and which is unsupported at its upper end due to the 60 hinged sides, is thus made strong and rigid without materially increasing the weight or cost of manufacture. Suitable strap braces 99 and 100 may also be provided for supporting the outer ends of the cross bars 66 65 from the sills.

In Fig. 12 suitable means is shown for raising and lowering each of the hinged sides, comprising a stub shaft 102 having a crank 103 on its forward end and a sprocket wheel 104 to engage a chain 105 running over 70 a like sprocket upon a stud 106 made fast to the hinged side with its longitudinal axis in coincidence with the axes of the hinge pin-tles. By turning the crank, the side may be quickly and easily swung downward or upward into closed position where it may be held by latch bars 107 similar to the bars 14, each of which are operated by a handle bar 108 pivoted to the side within reach of the operator standing on the ground and connected at one end to the latch bar intermediate the ends thereof by a link 109.

One of the main features of this machine is the arrangement of the rack sides whereby as the load settles and is moved rearwardly, it does not bind against the sides as it otherwise would, and this is due to the inclined and oblique relation of the sides which frees the load and permits the conveyers to readily move it against the beaters. 85

Another feature is the combination of longitudinal supporting sills adapted to be secured directly to the bolsters, with a plurality of carriers between and outside of the sills covering the bottom of the rack which 90 may therefore be made wide enough to give the desired capacity and will have the necessary strength and lightness of construction. 95

Other features of the invention are the means by which the operator may adjust the 100 tension on the load so as to hold it properly in contact with the conveyer and thereby allow the latter to force it evenly against the beaters; and the disposition of the adjusting members so that they may be readily 105 reached from the operator's station and permit the user to vary the feed as he desires while the machine is in operation.

Obviously changes in the details of construction may be made without departing 110 from the spirit of my invention and I do not limit myself to the particular form or arrangement of parts.

What I claim is:—

1. In a straw spreader, the combination 115 with a running gear and traction wheels therefor, of a rack mounted on the running gear having a bottom and sides which are inclined inwardly toward their upper edges, means for ejecting straw from the rack, and 120 means for transmitting motion from the traction wheels to operate said ejecting means.

2. In a straw spreader, the combination 125 with a running gear and traction wheels therefor, of a rack mounted on the running gear having sides which diverge rearwardly and converge toward their upper edges, means in the bottom of the rack for moving straw rearwardly thereon, means at the rear 130

end of the rack for ejecting straw, and means for transmitting motion from the traction wheels to operate said moving and ejecting means.

5. In a straw spreader, the combination with a running gear and traction wheels therefor, of a rack having longitudinal sills, cross bars secured to the sills and extending laterally beyond the traction wheels, a floor 10 on the cross bars, and rack sides secured to the cross bars near their ends in an inwardly inclined position, ejecting means supported by the rear ends of the sides, a carrier movable over the floor, and means for transmitting motion from the traction wheels to drive the carrier and ejecting means.

4. In a straw spreader, the combination with a running gear and traction wheels thereon, of a rack on the running gear having longitudinally extending supporting sills, cross bars on said sills extending laterally beyond the sills and beyond the traction wheels, a floor on said cross bars forming the bottom of the rack, and rack sides secured to 25 the cross bars near their ends, a plurality of separate endless carriers movable longitudinally between and at the sides of said sills and over the floor, and means for transmitting motion from the traction wheels to operate the carriers.

5. In a straw spreader, the combination with a running gear and traction wheels therefor, of a rack having a pair of longitudinally extending parallel supporting sills 35 and a rack bottom on said sills extending laterally over and beyond the traction wheels, an endless carrier movable longitudinally of said sills between the same and over said rack bottom, an endless carrier at 40 each side of the pair of sills movable longitudinally thereof and over the rack bottom, said carriers together traversing substantially the entire upper surface of said bottom, and means for operating said carrier.

45. 6. In a straw spreader, the combination with a running gear and traction wheels for the same, of a rack comprising longitudinally extending parallel sills secured to the running gear, cross bars spanning the sills 50 and extending laterally beyond the same and beyond the traction wheels, a rack bottom on said cross bars, stanchions secured to the cross bars near the ends thereof and extending upwardly therefrom, in an inwardly inclined position, longitudinal strips secured to the stanchions and forming therewith rack sides which converge toward the upper edges, shafts extending across the ends of the rack, a plurality of endless carriers passing around said shafts and over and beneath said rack bottom longitudinally of said sills 60 at each side of each sill, and means for operating the carriers.

7. In a straw spreader, the combination 65 with a running gear having bolsters and

traction wheels for the gear, of a rack having a pair of longitudinal sills secured to the bolsters, cross bars secured to the sills and extending laterally therefrom beyond the traction wheels, a rack bottom on said cross bars 70 near the ends in a rearwardly diverging and upwardly converging position, a shaft mounted in bearings at one end of the rack bottom, a plurality of independent short 75 shafts mounted in bearings at the opposite end of said rack bottom, an endless carrier passing around each short shaft, beneath the bottom around the other shaft and over the rack bottom, there being a carrier between 80 the sills and a carrier adjacent to the outer side of each sill movable longitudinally thereof and said carriers together traversing substantially the entire upper surface of 85 said bottom, and means for turning the said shaft for operating the carriers.

8. In a straw spreader, the combination with a running gear, and traction wheels, of a rack comprising longitudinal sills, cross bars secured to and extending laterally beyond the sides of said sills, stanchions secured to said cross bars near their ends in an inwardly inclined position, and connected by longitudinal strips to form rack sides, certain of said stanchions at one end of the 90 rack being extended to the upper edge of the sides to form a rigid supporting frame for the support of ejecting devices, the other of said stanchions being made in two parts hinge connected and the upper parts connected by strips to form movable side sections, ejecting devices mounted on the said end stanchions, and means for transmitting motion from the traction wheels to drive 95 said ejecting devices.

9. In a straw spreader, the combination with a running gear, and traction wheels therefor, of a rack comprising longitudinal sills, cross bars secured to said sills and extending laterally therefrom beyond the traction wheels, rack sides comprising stanchions secured to said cross bars near their ends and longitudinal strips secured to the stanchions, the end stanchions at one end 100 of each side being extended below the cross bars and extended upwardly to the top of the sides, a cross member connecting the lower ends of said end stanchions and secured to the ends of said sills, beaters mounted on said end stanchions, diagonal brace members secured to said end stanchions near the upper ends thereof and extended downwardly therefrom across the 105 said sides, and means for transmitting motion from said traction wheels to said beaters.

10. In a straw spreader, the combination of a rack having sides which converge upwardly, means for feeding material from the rear end of the rack and moving the 110

same rearwardly therein, a presser at the top of the rack to engage the material and press the same downwardly in the rack, and means for operating said feeding means.

5 11. In a straw spreader, the combination of a rack having sides which converge upwardly and diverge rearwardly, a carrier in the bottom of the rack for moving the straw rearwardly, means at the rear end of the rack for feeding the straw therefrom, a presser for forcing the straw downwardly in the rack upon the carrier, a tensioning device for the presser, and means for operating the carrier and the feeding means.

10 12. In a straw spreader, the combination of a rack having sides which converge upwardly and diverge rearwardly, a carrier in the bottom of the rack, beaters at the rear end of the rack, a pivoted presser supported

20 at the top of the rack and adapted to swing downwardly and rearwardly therein, and means for operating said carrier and beaters.

13. In a straw spreader, the combination

of a rack, a carrier in the bottom of said rack, presser arms pivotally supported at one end upon the rack near its top to swing downwardly therein, tension means to vary the pressure of the swinging movement upon the straw, and means for operating the carrier.

5 14. In a straw spreader, the combination of a rack having sides which converge upwardly and diverge rearwardly, a carrier in the bottom of the rack, beaters at the rear end of the rack, yieldable presser arms pivotally supported at one end on said sides to swing downwardly and rearwardly in the rack, means for varying the action of said yielding means, and means for operating the beaters and carrier.

10 In testimony whereof I affix my signature in presence of two witnesses.

DUDLEY GARST.
